UNITED STATES PATENT OFFICE.

AUGUST SCHILLING, OF SAN FRANCISCO, CALIFORNIA.

SHIPPING CONTAINER.

Application filed September 6, 1921. Serial No. 498,803.

To all whom it may concern:

Be it known that I, AUGUST SCHILLING, a citizen of the United States, residing at the city and county of San Francisco and State of California, have invented certain new and useful Improvements in Shipping Containers, of which the following is a specification.

This invention relates to a shipping container of comparatively light weight adapted to be cheaply constructed for containing relatively large shipments for retail sale of a cheap commodity, such as salt.

The principal object of this invention is to provide a container of the above type which, when packed, is provided with a normally sealed opening formed in the body of the container wall, and which requires but slight manual effort to lift the same when it is desired to remove the contents from the container. A further object is to provide a container one wall of which is constructed of two laminations adhesively secured together, enabling the ready formation therein of a content removal opening, which is normally sealed until manually broken.

With the above mentioned and other objects in view, the invention consists in the novel construction and combination of parts hereinafter described, illustrated in the accompanying drawing and pointed out in the claims hereto appended; it being understood that various changes in the form, proportion, size and minor details of construction within the scope of the claims may be resorted to without departing from the spirit or sacrificing any of the advantages of the invention.

To more fully comprehend the invention, reference is directed to the accompanying drawing, wherein—

Fig. 1 is a view in top plan of a container, disclosing the preferred embodiment of my invention.

Fig. 2 is a broken sectional view, disclosing more fully my invention.

In the drawing—1 indicates a container side wall constructed of any suitable material, and on the same, preferably at the head end rests an end closure head 2 constructed of the outer lamination 3 and the inner lamination 4, the meeting faces of which are secured together by an adhesive applied as at 5. The inner lamination 4 is of a lesser diameter than 3, affording an

annular groove 6 in the head for the reception of the upper end of the wall 1. If desirable, suitable conventional strap clamps 7 having inwardly punched teeth 8 may be utilized to secure the head to the container wall. In fact, any suitable form of securing means may be employed.

At spaced points it is desirable to unite the laminations 3 and 4 by a permanent means, such as a rivet 9 passed therethrough, and prior to securing the head to the container wall the inner lamination 4 is provided with an annular cut 10 extending entirely therethrough, and the outer lamination 3 is provided with a similar cut 11 extending entirely therethrough, but the cut 11 being of a greater radius than cut 10 provides an outer closure section 12 of a diameter larger than the inner closure section 13 lying immediately below the same. In the formation of these sections, the adhesive between the uncut portion of the inner lamination 4 and the overhanging portion of the outer closure section 12 is not broken, or serves as a means for holding the closure formed by the members 12 and 13 in position in the head 2.

For removing the head, any suitable means may be employed, that illustrated consisting of a ring 14 held by a U-clamp 15 passing through the members 12 and 13, as indicated in Fig. 2.

This closure member for the opening may be of any suitable diameter, dependent on the commodity originally packed in the container, and it will be observed that when the closure member formed by the members 12 and 13 is removed, the container end is not destroyed, and the container is adapted for use in the transporting of other commodities or for storage purposes.

I claim:—

1. A container formed of a side wall and an end wall secured to the side wall, said end wall being formed of two layers of material adhesively secured together in superimposed relation, said layers being annularly cut each for its full depth affording a removable closure for the container consisting of two members of different diameters one lying within the other, said closure adapted for initial removal on the breaking of the adhesion between the cut portion of the larger member and the uncut portion of the layer surrounding the smaller member.
2. A container formed of a side wall and

an end wall secured to the side wall, said end wall being formed of two layers of material adhesively secured together in superimposed relation, said layers being annularly cut each for its full depth affording a removable closure for the container consisting of two members of different diameters one lying within the other, said closure adapted for initial removal on the breaking of the adhesive between the cut portion of the larger member and the uncut portion of the layer surrounding the smaller member, and means passing through said closure forming member affording a handle therefor.

3. A container formed of a side wall and an end wall secured to the side wall, said end wall being formed of two layers of material adhesively secured together in superimposed relation, said layers being annularly cut each for its full depth affording a removable closure for the container consisting of two members of different diameters, the inner member of smaller diameter lying within the other member, said closure held in position by the adhesive between the portion of the outer member projecting beyond the inner member and the uncut portion of the inner layer surrounding the smaller member.

4. A container, one wall of which is formed of two layers of material adhesively secured together in superimposed relation, the outer of said layers being annularly cut for its full depth forming a removable portion and the inner of said layers being annularly cut for its full depth to form a removable portion lying within the outer removable portion, said portions adapted for removal as a unit on the breaking of the adhesive uniting the removable portion of the outer layer to the uncut portion of the inner layer.

5. A container, one wall of which is formed of a plurality of layers of material adhesively secured together in superimposed relation, certain of said layers being cut to form a removable portion, certain other of said layers being cut to form a removable portion lying within the periphery of the other removable portion affording a supporting flange on the wall beneath said first mentioned removable portion, said removable portions adapted for removal as a unit from the container on the breaking of the adhesive uniting the first mentioned removable portion and said flange.

In testimony whereof I have signed my name to this specification.

AUGUST SCHILLING.
